UNITED STATES PATENT OFFICE

ALEXANDER KIRK RIDER, OF WALDEN, NEW YORK.

EXPLOSIVE-GAS ENGINE.

SPECIFICATION forming part of Letters Patent No. 292,178, dated January 22, 1884.

Application filed June 7, 1883. (No model.)

To all whom it may concern:

Be it known that I, ALEXANDER K. RIDER, of Walden, in the county of Orange and State of New York, have invented certain new and 5 useful Improvements in Explosive-Gas Engines; and I do hereby declare the following to be a full, clear, and exact description of the invention, such as will enable others skilled in the art to which it appertains to make and 10 use the same.

My invention relates to an improvement in explosive-gas engines, the object being the provision of engines of this class with improved electrical appliances for igniting the charges.

With these objects in view my invention comprehends devices for producing one or more magnetic sparks by the contact and separation of suitable terminals located within the motive cylinder.

In the accompanying drawings, Figure 1 is a view in vertical section, through the motive cylinder and igniting-bonnet, of an explosive-gas engine embodying my invention. Fig. 2 is an exterior view of the bonnet, showing the 20 devices employed for separating the terminals. Fig. 3 is an interior view of the bonnet, showing a modification of the devices for interrupting the circuit. Figs. 4, 5, and 6 are interior views of bonnets, respectively, embodying 25 modified forms which the circuit-breaking devices may assume.

A represents the motive cylinder of an explosive-gas engine, the piston B thereof being driven by the explosion of a charge of mixed 30 gas and air in the chamber C. An aperture, D, formed in the said cylinder and opening into chamber C aforesaid, is adapted to receive the igniting-bonnet E, through which the arbors F and G extend, the outer ends of the 35 said arbors being, respectively, connected to the opposite poles of a suitable dynamo-electric machine.

The inner end of the arbor F, which preferably consists of a simple steel rod, is provided 40 with a disk, H, the same having an arm, I, attached to it, as shown. A short platinum cylinder, J, extending transversely through the outer end of the said arm, forms one terminal 45 of the circuit-breaker, a similar cylinder, K, mounted in the inner end of the arbor G, forming the other terminal thereof. The said arbor G, which is preferably formed of copper,

is insulated from the bonnet by an envelope, N, of asbestos or other suitable material.

For the purpose of forming a tight joint for 55 the arbor F, which is rotated on its longitudinal axis, as will be hereinafter described, the inner end of the said arbor is provided with a valve-face bearing, O, arranged to fit in a suitable recess, P, formed in the inner face of the 60 bonnet, the said valve-face being maintained in position in the recess by means of a spring, R, encircling the arbor and interposed between a drum, S, secured to the outer end thereof, and the bonnet. This spring also operates to take up any wear resulting from friction between the surfaces in contact.

By use of the valve-face and recess, as described, stuffing-boxes are done away with 70 with obvious advantage.

The terminals J and K are separated for the production of the spark relied upon to ignite and explode the successive charges introduced into the cylinder by a slight rotation of the arbor F. This is effected by providing the outer 75 end of the arbor with the drum S, to which an arm, T, of steel or brass, is rigidly secured. The arm may, however, be directly attached to the arbor without the intervention of the drum. A momentum-block, U, attached to 80 the free end of the said arm, is arranged to be engaged and depressed once during every revolution of a rotating finger, V, the same being actuated by any suitable motive agency. So far as the terminals are concerned, the depression of the block and arm operates only to 85 bring them in closer contact. When, however, the block is released from the finger, the tension acquired by the arm causes it to recoil with the effect of slightly rotating the arbor F 90 and separating the terminals J and K, which are almost immediately brought in contact again by the reaction of the momentum-block.

A spring, W, attached to the arm in the manner shown, is arranged to absorb the vibrations thereof. The use of the momentum-block enables the circuit to be broken and closed very suddenly, which is a desideratum in the application of electricity to the ignition of the charges, for the reason that the more abrupt 100 the breaking of the circuit and the reversal of the current the stronger the spark obtained. The strength of the spark is greatly augmented by the saturation of the "field-of-force" mag-

nets of the dynamo-electric generator between the successive interruptions of the circuit, for as the said magnets are practically demagnetized by every interruption of the circuit, the 5 spark produced embodies the accumulated effect of as many turns of the armature as were required to saturate them. My improved application of electricity to gas-engines is eminently adapted to make this desirable mode of 10 increasing the strength of the spark available. The intensity of the spark may also be increased without the use of a coil by simply using finer wire in the armature and "field-magnets." The magnetic spark thus derived 15 is of very high calorific power, and will ignite gases and mixtures of gas and air which cannot be ignited by a flame or by electricity, as heretofore applied.

The mechanism shown in Fig. 3 is the same 20 as that shown in Figs. 1 and 2, except that it is adapted to be operated by a vibrating instead of a rotating finger. The adaptation for this purpose consists simply in a rocking bearing, X, pivoted to the momentum-block U, 25 and held in a position of readiness to be engaged by the downstroke of the vibrating finger V by a spring, Y, arranged as shown. On the upstroke, the finger elevates the bearing against the force of the spring Y and passes 30 it without throwing the arm T into vibration.

In the modified device shown in Fig. 4 of the drawings the arm I is replaced by a copper plate, Z, provided with a contact-point, A', made integral with or attached to it. On the 35 other hand, the terminal K of the arbor G is replaced by a volute platinum spring, B', the outer end of the same being normally engaged with the contact-point A' aforesaid. The interruption of the circuit is effected by the 40 lateral deflection of the plate, which causes the separation of the point and spring. A block, C', of porcelain or other suitable material, is mounted in the plate Z, and arranged to engage with the spring and prevent the 45 same from springing up and interfering with the return of the plate after deflection. Banking-pins D', respectively located on opposite sides of the plate, are designed to define the limit of vibration in each direction. As here- 50 in shown, the devices employed for vibrating the plate are the same as those shown for separating the terminals of the device shown in Figs. 1 and 2; but any other suitable means of interrupting the circuit by contact and separation may be adopted.

In the modification shown in Fig. 5 of the drawings the circuit is broken by the escapement of a volute platinum spring, E', on a copper ratchet-wheel, F', the said ratchet and 55 spring being respectively secured to the inner ends of arbors corresponding to the arbors F and G of Figs. 1 and 2. The ratchet is rotated by means of a vibrating arm, G', provided with a pawl, H', the latter being ar- 60 ranged to engage with the teeth of a ratchet mounted on the arbor of the ratchet F' and located on the exterior of the bonnet. Every

successive vibration of the arm G' produces one escapement of the spring E' on the ratchet F', the circuit being interrupted at every 70 escapement. If desired, the spring E' may be replaced by a pawl rigidly secured to the arbor, which must be arranged to be rotated through a short arc. For this purpose it is 75 inclosed in a copper sleeve, the same being insulated in the bonnet by an envelope of non-conducting material. The object in using the sleeve is to provide means for obtaining the valve-face joint or bearing, which cannot be arranged like the uninsulated arbor on account of the non-conducting envelope. The 80 pawl would, of course, have a suitable spring associated with it to maintain it in normal contact with the ratchet.

The modified arrangement shown in Fig. 6 85 of the drawings is similar to that represented in Fig. 5. It comprehends the use of a copper disk, I', arranged to be partially or completely rotated, and provided with a series of porcelain cylinders or pins, J', which break 90 the continuity of the periphery of the disk, to the contour of which they are conformed. The outer ends of these cylinders are further conformed to the valve-face bearing on the reverse face of the disk. A volute platinum 95 spring, K', secured to the arbor, corresponding to the arbor G of Figs. 1 and 2, is arranged to engage with the periphery of the disk, the rotation of which alternately engages the spring with the segments of the periphery thereof and the porcelain cylinders, and thus interrupts the circuit. The circuit 100 may be broken by rotating the disk through a short arc; or the disk may be completely rotated one or more times to produce a succession of sparks. Again, it may be arranged to be continuously rotated and the current short-circuited around it and interrupted, as 105 desired. No means of actuating the disk are shown, the devices employed being chosen with reference to the plan adopted for its operation. If desired to rotate the disk through short arcs, a pinion mounted on its arbor, and adapted to receive an impulse at every revolution of a revolving finger, may be employed. 110 On the other hand, if desired to rotate it completely, the pinion may be arranged to be actuated by a suitable train of wheels.

The principle of producing a spark within the motive cylinder of the engine by the contact and separation of terminals is obviously capable of embodiment in many different devices, and I do not restrict myself to those herein shown, which depend upon the movement of at least one of the terminals in a circular path. This plan need not be adhered to, although it seems best adapted to fulfill the requirements demanded.

The arbor to which the movable terminal is secured should be invariably provided with 120 the valve-face bearing, as and for the purpose described, and if the arbors of both terminals are rotated both arbors should be so arranged.

In view of the modifications herein suggested,

and others of which the invention is obviously susceptible, I would have it understood that I do not limit myself to the exact construction and combinations of parts herein shown and described, but hold myself at liberty to make such changes and alterations as fairly fall within the spirit and scope of my invention.

Having fully described my invention, what I claim as new, and desire to secure by Letters 10 Patent, is—

1. In an explosive-gas engine, the combination, with a bonnet inserted through the cylinder, of an electric circuit-breaker supported by said bonnet, the terminals being located 15 within the motive cylinder, substantially as set forth.

2. In an explosive-gas engine, terminals located within the motive cylinder, one being movable, a spring-arm connected with the 20 movable terminal, and means for laying the said arm under tension and allowing it to suddenly recoil to move the movable terminal and interrupt the circuit, substantially as set forth.

25 3. In an explosive-gas engine, an igniting-bonnet, arbors extending through said bonnet, terminals respectively secured to the inner ends of said arbors, and means to move one arbor and separate the terminals, substantially as set forth.

4. In an explosive-gas engine, an igniting-bonnet, arbors extending through said bonnet, terminals secured to the inner ends of the arbors, and means to rotate one of the arbors 35 on its longitudinal axis for the purpose of separating the terminals, substantially as set forth.

5. In an explosive-gas engine, an igniting-bonnet, arbors extending through the bonnet, means to insulate one of the arbors therein, terminals attached to the inner ends of the arbors, and means to move one of the arbors to separate the terminals, substantially as set forth.

45 6. In an explosive-gas engine, an igniting-bonnet, arbors extending through the same, means to connect the outer ends of the arbors with a generator of electricity, terminals associated with the inner ends of the arbors, and 50 devices to move one arbor or both to separate the terminals, substantially as set forth.

7. In an explosive-gas engine, an igniting-bonnet, arbors extending through the same, terminals associated with the inner ends of the arbors, which are provided, one or both, with 55 valve-face bearings fitting in suitable recesses located in the inner face of the bonnet, substantially as set forth.

8. In an explosive-gas engine, an igniting-bonnet, arbors extending through the same, 60 terminals associated with the inner ends of the arbors, which are provided, one or both, with valve-face bearings fitting in recesses located on the inner face of the bonnet, and means to maintain the said bearings in the recesses, 65 substantially as set forth.

9. In an explosive-gas engine, an igniting-bonnet, arbors extending through the same, terminals associated with the inner ends of the arbors, one of which is arranged to be rotated 70 on its longitudinal axis, a vibratory arm having one end rigidly secured to the movable arbor, and means for laying the arm under tension and suddenly releasing it, substantially as set forth.

10. In an explosive-gas engine, an igniting-bonnet, arbors extending through the same, terminals associated with the inner ends of the arbors, one of which is movable, a vibratory arm secured to the movable arbor, a momentum-block attached to the outer end of the arm, and means for laying the arm under tension and suddenly releasing it, substantially as set forth.

11. In an explosive-gas engine, an igniting-bonnet, arbors extending through the same, 85 terminals associated with the inner ends of the arbors, one of which is movable, a vibratory arm secured to the movable arbor, and means for laying the arm under tension and suddenly releasing it, and a spring to absorb the vibrations of the arm after its recoil, substantially 90 as set forth.

In testimony whereof I have signed this specification in the presence of two subscribing witnesses.

ALEXANDER KIRK RIDER.
